(57) **CLAIM**

The ornamental design for a bookshelf speaker, as shown and described.

DESCRIPTION

FIG. 1 is a front perspective view of an embodiment of a bookshelf speaker in accordance with our new design;

FIG. 2 is a front elevation view of the bookshelf speaker of FIG. 1;

FIG. 3 is a rear elevation view of the bookshelf speaker of FIG. 1;

FIG. 4 is a right-side view of the bookshelf speaker of FIG. 1;

FIG. 5 is a left-side view of the bookshelf speaker of FIG. 1;

FIG. 6 is a top view of the bookshelf speaker of FIG. 1; and, FIG. 7 is a bottom view of the bookshelf speaker of FIG. 1. The broken lines shown in the drawings are only provided to illustrate the environment of the design, and form no part of the claimed design.
